(57) **CLAIM**

The ornamental design for an offset cable tie, as shown and described.

DESCRIPTION

FIG. 1 is a perspective view of a first embodiment of the offset cable tie;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front end elevation view thereof;

FIG. 7 is a back end elevation view thereof;

FIG. 8 is a perspective view of a second embodiment of the offset cable tie;

FIG. 9 is a right side elevation thereof;

FIG. 10 is a left side elevation thereof;

FIG. 11 is a top plan view thereof;

FIG. 12 is a bottom plan view thereof;

FIG. 13 is a front end elevation view thereof; and,

FIG. 14 is a back end elevation view thereof.

The broken lines depict environmental subject matter and form no part of the claimed design. The boundary lines in FIGS. 3 and 10 depict the boundary of the claim. The broken away symbols in the drawing indicate the appearance of any portion of the article between the broken lines forms no part of the claim.

1 Claim, 4 Drawing Sheets
